Patented Sept. 24, 1968

212,300

COMBINED FACE AND HANDS FOR A CLOCK

Leo M. Margolis, Jamaica, N.Y., assignor to Coro, Inc.,
Providence, R.I., a corporation of New York

Filed Oct. 23, 1967, Ser. No. 9,107

Term of patent 14 years

(Cl. D42—7)

FIG. 1

FIG. 2

FIG. 3

FIG. 1 is a front elevational view of a combined face and hands for a clock showing my new design in its eight o'clock position;

FIG. 2 is a front elevational view of a combined face and hands for a clock showing my new design in its twenty minutes past eight o'clock position; and

FIG. 3 is an edge view thereof.

I claim:

The ornamental design for a combined face and hands for a clock, substantially as shown and described.
